UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIO DISTRIBUTING SYSTEM.

Application filed December 21, 1923, Serial No. 681,991. Renewed March 8, 1927.

My invention relates to systems of communication, and particularly to broadcasting systems.

The present application is a continuation in part of my copending application, Serial Number 581,829, filed Aug. 14, 1922, Patent Number 1,522,357, reissued as Reissue No. 16,231, and has for its objects, among others, the following: To organize broadcasting service on a commercial basis, and to control the service units or receiving stations so that the various contingencies incidental to commercial operation may be efficiently met, such as maintenance, supervision, and the imposition and collection of charges; to localize each unit of a system, so that it may be tested and supervised; to standardize the distributed unit agencies in a system, while enabling them to receive messages broadcasted on various wave lengths; to control broadcasting so that it may supplement in organized service existing telephone exchange systems.

The foregoing objects are attained by the method of operation to be hereinafter described, which, it is to be understood, is typical, and is to be taken as such, for purposes of definition and not of limitation of the invention. According to this method I provide a system having for its basis the distribution among regular subscribers in localized areas, of standardized receiving instruments, each local area taking its broadcasting service, by wire guided waves, from its own central station on such wave length or frequency as may be fixed and determined for that area. Each receiving station is connected to the local central station by a wire circuit, through which both distribution and the control of the local station are attained. This arrangement enables me conveniently to feed the substations with current from central for divers purposes, to control the receiving instruments at said stations from the central station, and to meter the broadcast service rendered for the purpose of making charges. Other benefits flowing from this arrangement will sufficiently appear from the detailed description hereinafter.

By using standardized receiving units, all uniformly tuned with their line circuits to the wave length of the local distributing station, I am able to provide said distributing station with sensitive and powerful re-

ceiving and relaying apparatus and circuits, whereby distant stations may be picked up, and various wave lengths may be received by variable tuning and their modulations relayed over the wires on the standard local wave length to the subscribers, who can receive and recognize the original messages thus relayed, without the necessity of variable tuning or highly sensitive instruments at their stations. With the above arrangement for distribution, the ultimate receiving instruments are reduced to the simplest form compatible with their purpose because they are practically unaffected by atmospheric conditions or "static", and when once tuned remain in tune, unless it is desired to give a small range of adjustment for sharpening.

My invention is illustrated in the accompanying drawings in which:

Fig. 1 is a diagram showing a general system embodying the same;

Fig. 2 is a diagram showing a central station telephone switchboard, subscribers' lines terminating thereon, and subscribers' telephones connected thereto;

Fig. 3 is a diagram to be read in connection with Fig. 2, showing the broadcast receiving set at one of the subscriber's stations, and the radio switchboard and associated equipment at the central station;

Fig. 4 is a diagram showing a substation battery charged and controlled over a phantom circuit imposed on a metallic magneto telephone circuit;

Figs. 5, 6, 7 and 8 are schematic circuits showing methods of connecting the radio battery with relation to the centralized telephone battery; and

Fig. 9 is a diagram of a modified arrangement of circuits.

Fig. 10 is a circuit diagram of a modification of the system, for broadcasting over the wires.

Fig. 11 is a diagram of a broadcast relay unit adapted for use with the circuits of Fig. 10.

Figs. 12, 13, 14, and 15 are simplified or schematic diagrams of different conditions of the circuits under different conditions of service.

Referring to Fig. 1, 1, 2 and 3 represent telephone subscribers' stations connected by wires 4, 5 and 6 to the central telephone exchange 7, constituting the distributing cen-

ter for the area in which local subscribers 1, 2, 3, etc., are located. Superposed upon this telephone system is a radio telephone system comprising a central station 8 and 5 subscribers' stations 1^a, 2^a, 3^a, etc. The central radio station or exchange is provided with switchboards and a complete broadcasting equipment, and the subscribers' stations 1^a, 2^a, 3^a, etc., are provided with receiving 10 instruments all standardized for the same wave length, and adapted to respond to the waves radiated from the central station 8. The interrelation between the telephone system and the radio telephone system is by 15 means of physical connections indicated at 1^b, 2^b and 3^b at the subscribers' stations, and multiples or trunk extensions 15 from the telephone exchange switchboards to the radio broadcast service switchboard in station 20 No. 8. The detail of these connections will appear hereinafter, but it should be stated here that the system of connections is such that telephone wired traffic has the right of way over the wires, while the radio traffic has 25 the right of way over the radio side of the system. The arrangement is such that the radio operator cannot interfere with telephone operation, nor can a telephone operator interfere with the radio operation, al- 30 though under proper conditions each can act freely by way of borrowing facilities from the other. At all times, should a question of precedence arise, the apparatus is arranged so as automatically to cut off the 35 radio connections and to leave the wired lines clear for telephonic use.

Stations 12, 13 and 14 in this figure are 40 typical of indifferently located distant stations which may or may not be a part of this particular system. As the figure is typical only, no attempt has been made to give the geographical location of such stations or to show the actual arrangement and distribution of the telephone centers through which 45 final broadcasting to the subscribers must take place. The main purpose of this figure is to crystallize the method employed, by which the development of a very large number of unrelated individual receiving stations is replaced by an orderly system of distribution through the telephone centers, whereby the individual receiving instruments are localized, maintained, controlled, and supplied with definite service through 50 regular channels, for which a definite charge can be made and collected in the manner usual in wired systems of communication. Inasmuch as the number of wave lengths available for transmission is 55 limited in the present state of the art, advantage is taken of the organized system of wire distribution and localization to create a phantom system controlled and guided thereby.

55 Briefly stated, as indicated in Fig. 1, each

radio central station or radio department of a telephone exchange, is not only provided with broadcasting equipment for its subscribers, but also with radio receivers adjustable by tuning to wave lengths allotted 70 to such stations as those indicated at 12, 13 and 14, as well as primary stations maintained and operated by or under the direction of the telephone organization itself. By means understood in the art, messages 75 received at the radio central stations are relayed on their respective standard wave lengths to the local subscribers.

Referring to Figs. 2 and 3, I have therein shown circuits of the central office and sub- 80 station equipments and connections, Fig. 2 representing the telephone side of the system, and Fig. 3 the radio broadcast side of the system. Before proceeding to detail description it may be noted that in accordance 85 with standard telephone practice, provision is made for keeping the telephone lines and central office circuits clear of all grounds or other disturbing connections during conversa- 90 tion. When the broadcast receiving goes into service, by closing the filament switch its operation in receiving is identical with that of any radio receiver, and in the event that use is made of any transmission of waves over the line wires, as will be hereinafter 95 pointed out, said waves will be at a frequency above or below the limits of audition. In the present diagram, Figs. 2 to 9 inclusive, I have shown the circuits arranged with nothing 100 but continuous current for radio purposes over the telephone line wires. This is the simplest form of control and the one nearest to present-day telephone practice, and is absolutely certain not to produce any disturbance in adjacent conductors in the 105 telephone cables. Each broadcast receiving set is provided with a cut off relay energized when the telephone set goes into commission, either by calling or being called, and at the central office whenever the radio operator 110 takes control of the line, he disables it in the usual manner by pulling up the cut off relay at the telephone switchboard, this however being subject to the condition that a special tone test may be put on, so that all 115 operators may know that the line is held on the radio board, and subject to interruption for telephone connection. I prefer to use this tone test only with the radio operator's testing plug, because his regular connecting 120 plug includes within its functions that of connecting a subscriber through the station amplifier to the broadcasting transmitting set, and a connection of this character should not be interrupted without permission.

Referring now to the diagrams, Fig. 2, A and A' are two subscribers' stations connected by line wires 16—17 and 18—19 respectively to the central station C where they 125 terminate on jacks J and J'. P—P' are

plugs forming the terminals of a cord circuit 20—21, 22—23, having a bridged repeating coil I, ringing and listening keys K and K', supervisory signals s—s' and 5 bridging connection to the main battery B. The same battery is shown supplying current to the line relays L, L', and through contacts at the cut off relays L², L³ to the respective lines for calling purposes. In this 10 system, when a subscriber takes down his receiver, the line relay lights its lamp, which is extinguished when the operator inserts the answering plug. Battery supply for the connected lines is thereafter taken through the 15 cord circuit 20—22, 21—23, in a manner well understood in the art. When the substation telephones are out of service, with their receivers hanging on their hooks, the line circuits are conductively open for direct current 20 rent, leaving the ringers Q and Q' in circuit for alternating ringing current passing through the condensers q—q'.

Referring now to Fig. 3, it will be observed that the radio switchboard which I 25 have designated generally by the letter R, is connected to the subscribers' lines by multiple taps marked 16^a, 17^a, and 17^b, and 18^a, 19^a, 19^b. These terminate on multiple jacks J², J³, corresponding to the multiple jacks 30 on the telephone switchboard. These multiple connections 16^a, 17^a, etc., instead of being permanently connected to the subscriber's multiple jacks, may take the form of order trunks, less in number than the number of 35 lines and terminating in plugs or jacks near the telephone switchboards. This would be desirable where changes of terminal connections in the standard wiring are to be avoided, and would be especially advanta- 40 geous where the proportion of subscribers taking special service is small. It should be noted that throughout this system the tip wires 16 and 18 with their branches are connected to ground, while the ring wires 45 17 and 19 and their branches, are connected to battery. This is extended into the radio side of the system for the purpose of securing proper balance between the main battery or power plant of that side and the main 50 battery or power plant of the telephone side of the system.

At the subscribers' stations taps are also taken off from the telephone terminals to the broadcast receiver terminals as indicated at 18^c, 19^c, and 19^a. (The broadcast receiver is shown only at one substation for sake of simplicity of illustration. The two branches 19^c and 19^a are taken from the ring or battery side 55 of the line 19, and are connected to opposite terminals of the winding of a relay L⁴, which constitutes the substation cut off relay for the radiophone. The winding of this relay is bridged by a condenser q² through which 60 both ringing and voice currents can pass

without substantial impedance. Where the radiophone is attached to a party line substation, this relay L⁴ may be omitted, since on such party lines there are usually grounds on one side or the other. As will presently 70 appear, the radio circuits described herein are applicable to two-party or four-party lines, with individual metering of the party stations.

Normally, that is to say, when the telephone circuit is not in use, the cut off relay L⁴ is deenergized and as a consequence the wire 19^c is connected through a back contact of the relay through extension wire 24 to the branch 25 connected to the "A" battery 80 marked A₁ in Fig. 3. The wire 18^c similarly passes through a back contact of the relay to the extension wire 26 leading to test or listening relay L⁵ and ground. 18^c, it will be remembered, leads to the tip or ground 85 side of the line, therefore it is the side which in the broadcast receiver can be made use of with a permanent ground or grounds, without disturbing the balance of the telephone circuit.

The broadcast receiver at the substation A' is shown as comprising an antenna 28, tuned coupler 29, detector tube 30, audio amplifier tubes 31 and 32, and the usual 90 transformers 33, 34, 35, the last mentioned transmitting the amplified audio waves to the telephone receiver or loud speaker 36. The filament battery is A₁. The plate battery is B₁ and suitable tuning condensers and coils, tickler coil for regenerative effects, etc., are provided as required. I should remark in passing that this representation of the radio receiver is intended to be typical only. The present invention does not concern itself specifically with the design of 100 the local broadcast receiver sets, and other circuits and apparatus may be substituted for those shown in the diagrams without departure from the invention.

The relay L⁵ has four pairs of contacts, 110 one pair 27^a closing the wires 25 and 37 from battery A₁ to the filaments. The second pair 27^b closes the wires 25 and 38 so as to put battery A₁ on the broadcast transmitter T', and through the induction coil 115 I', to ground. The third and fourth pairs of contacts 27^c, 27^d, close the wires 39 and 40, forming terminals of the secondary induction coil circuit I', to the tip and sleeve side 120 of the telephone line respectively, through the back contacts of relay L⁴. The transmitter T' is shown hanging upon a hook switch H' controlling the connection of wires 41 and 42, constituting a parallel link 125 between the battery A₁ and the filament bus 43. Thus the filament can be heated and the broadcast receiver put in service either through the agency of the relay L⁵, or by the switch hook H'. The former is controlled by the radio operator at central, and 130

the latter by the subscriber at the substation. In addition to the hook, the subscriber has a manual switch h by which he can connect the battery wire 42 through a wire 44 to his transmitter T' , coil and ground, so as to energize his talking circuit. I provide an ordinary telephone receiver t' in series with the secondary of the induction coil I' , and I interpose a pair of condensers q^2 , q^4 5 between the secondary of the induction coil I' and the receiver t' on the one hand, and the terminals of relay L^5 on the other, so that while the subscriber by means of switch h can connect his phone $T'-t'$ for receiving 10 calls over the telephone line, he cannot originate calls thereover from the radio telephone extension.

Returning now to the central station, and particularly to the radio department 20 thereof shown in Fig. 3, T represents a broadcasting transmitter, symbolized in very simple form, but supposed to contain the usual elements of power supply, modulator, oscillator and aerial, with suitable 25 amplification of the audio waves supplied on the input side. The jack J^4 connected to the amplifier t^2 and thence to the transmitter T , symbolizes a group of such jacks or equivalent connecting means such as automatic switches, controlled by dials or keys 30 for connecting any of the wire lines to said radio transmitter. Detailed appliances, both for the switching and for the radio transmission, are well known in the art, and 35 need no specific description in this specification, my present invention having to do particularly with the method of transmitting by wave radiation to the substations, and of bringing in all conversation originating 40 or received at the substation radio telephone over the subscriber's wire line. This includes repetition of modulated radio waves received at the radiophone substation and 45 also originating messages gathered up and to be put through the amplifier t^2 on the transmitter T for broadcasting.

It may be explained here that the transmitter T for general purposes is assumed 50 to be the standard wave length transmitter for the local exchange area, to which all of the substations are tuned and upon which they depend both for original messages and programs and for those received and relayed from a distance. There are special 55 cases, however, in which certain groups of broadcast service subscribers may desire intercommunication among themselves, and I contemplate therefore the installation of duplicates of this transmitter, which may be 60 connected up for such group use. For example, a chess club desiring to meet, arranges a program, and at the appointed time its members attend at their broadcast receiving sets, all removing their transmitters T' from their hooks, while the radio 65

operator at the central station plugs up the multiples of their respective lines through their jacks J^2-J^4 , and connects them on to a special broadcasting transmitter of the type T . This plugging up may be carried 70 out in any desired manner, there being several ways well known in the art for thus connecting telephone lines together. The radio operator then supervises the operation, since any one of the connected subscribers may be speaking through the broadcasting transmitter to the others, and it is necessary to prevent interruption. The same might be said of any meeting of a 75 group of people held in this manner, the most valuable feature of this part of the invention being the absolute control afforded over the transmitted messages. The connection to the broadcasting transmitter is 80 solely within the control of the radio operator at the jack J^4 or any other suitable form of switch, and he has it in his power therefore to cut off connection at any time.

The cord circuit between plugs P^2 and P^3 in Fig. 3 is the same as the operator's cord 85 circuit in Fig. 2, but the radio operator also has special test cords such as that shown in the upper part of the figure connected to plug P^4 . Here the keys $K-K'$ are of standard construction, as in the other cords, and the test contact of the plug P^4 is connected through suitable resistance to the supervisory lamp s^2 to the radio battery B' , means 90 such as the commutator p^5 being provided to give special tone test on the test thimbles of the multiple jacks J , J' , J^2 , etc. The key K is also provided with suitable contacts, not shown, for applying signal current to the line while holding the relay L^5 energized, the signaling current being applied in any 95 known or other suitable manner capable of effecting the receiver t' or other signaling device. For example the ordinary howler signal current may be applied to the line conductors to operate the receiver t' through 100 the condensers in its circuit. It will be observed that the constant connection of the battery wire 24 at the substation to the bus wire 25 of the battery A_1 , produces charging 105 of that battery by the constant flow of current therethrough from the main radio battery B' at the central office. The amount of energy thus delivered to the battery A_1 depends upon the size of the line wires, and 110 the length of time available for such charging. As shown, the battery wire 24 is not cut off except when the cut off relay L^4 115 pulls up which is only when the line wire is in use for conversation. With No. 19 line wires, and using only the sleeve wire for 120 conduction, it would be possible to safely transmit from one-half ampere to two or three amperes, according to the line resistance and the voltage of the battery employed. Where this voltage is standard 125 130

manual telephone voltage, say 22, and the single wire resistance to the substation is from 25 to 50 ohms, it would be possible to maintain the battery A_1 continuously charged, provided the time of discharge be not too long extended, and the charging be not interrupted by other contingencies, such as the excessive telephone use of the line. In Fig. 4 of the drawing I show means for charging such a battery over a phantom circuit composed of the two sides of a magneto telephone line. Such a phantom circuit of course possesses still lower resistance than a single wire of the pair and correspondingly augments the amount of energy that may be delivered without a prohibitive loss. I wish to point out in connection with this, that radio instruments have recently been devised by the commercial radio corporations, and also by the United States Bureau of Standards, which employ rectified alternating current for lighting the filaments of the audion tubes, such currents being stepped down to the usual voltage of the filaments from the voltage of house mains or feeder lines. Using such a type of transformer and rectifier circuit, it is within the scope of my invention, to feed the filaments direct, and at the same time charge a floating storage battery A_1 , if desired, by transmitting over my line wire 19-19^c-24 a sine wave current at such voltage as will deliver the necessary energy.

Connected to the key K is a wire 50 containing a supplemental key k to connect the voltmeter or other suitable indicating instrument V and ground. The key K' serves to connect the operator's listening set, and also to put battery on the tip of the plug, by which means current is thrown out on the tip side 18 of the line, then through extension 18^c and back contact of relay L^4 to the winding of relay L^5 and ground. The operation of these test keys will be obvious from the description. Key k enables the operator to take a reading on the battery A_1 , the line resistance being known, and the main batteries B , B' being disconnected both at the cut off relays L^6 , L^7 from the line itself and by the back contacts of key K from the plug P^4 . This is the most important test because the lamp filaments can be observed by the subscriber, and any defect therein reported over the telephone. A companion test however enables the operator to determine whether the broadcast receiving instrument as a whole is functioning properly, assuming the transmitter T' to be hung upon its hook H' and as shown to have its mouth piece turned toward the emission orifice or diaphragm of the radio telephone receiver. Connection of battery B' to the relay L^5 causes the subscriber's telephone set T' , I' , to be connected to line and so to

the multiple jack J^3 , plug P^4 and the operator's head phone connected through the listening key K' . It is assumed of course that some form of broadcasting is going on from the transmitter T , so that the radio operator not only gets a test on the performance of the individual subscriber's radiophone, but also gets a test on his own broadcasting transmitter and on the relative tuning of the same with respect to the subscriber's station.

It should be noted that battery B' in Fig. 3 is connected to the ring wires 17^a, 19^a through the contacts of cut off relays L^6 , L^7 , energized in parallel with the line cut off relays L^2 and L^3 , either from the radio board or from the telephone switchboard. This enables the central office under all circumstances to keep a talking line balanced and supplied with current only through the connective cord or switch circuit, but as shown in Figs. 5 to 8 inclusive, the connections of the radio battery and that of the main battery are such that the balance is normally maintained, and current is supplied in such a way to the ring side of the line that no signaling apparatus on the telephone switchboard is affected thereby.

Fig. 5 shows the condition when a subscriber is talking through the telephone switchboard, the repeating coil I and the main battery B being shown as bridged across the line, and the radio battery B' permanently connected through the ring side to the subscriber's battery A_1 . Battery supply for both the subscriber's transmitter and the battery A_1 would as a matter of fact be drawn in due proportion from each of the centralized batteries B , B' , and the resultant effect would be to divide the load between the two parallel sources, without changing the normal condition.

Fig. 6 shows the same arrangement when the subscriber's telephone station is idle, and the main battery B is bridged across the line wires between the two windings 1-1' of the subscriber's line relay on the telephone switchboard; while the radio battery is connected in parallel to the ring side of the line through low resistance choke coils $x-x'$ which do not appreciably reduce the potential placed upon the line terminal of the winding 1 of the line relay, which, being exposed to balanced potentials, will not be energized unless the subscriber calls.

Figs. 7 and 8 show corresponding conditions with the cut off relay L^4 at the subscriber's station for detaching the battery A_1 when the subscriber is talking.

It is not considered necessary to actually adopt a permanent connection of the radio battery B' because telephone conversations are usually brief and the time of use of the current flow in the sleeve wire would not be thereby greatly curtailed. At the same time

I have provided means in the cut off relays L^6 , L^7 to disconnect the battery B' when the lines are plugged up for conversation as at x^2 in Figs. 5 and 7, and when such 5 cut off relays are employed, the choke coils $x-x'$ may be omitted, so that a practically perfect balance may be had across the terminals of the line relay 1. In other words, by using the cut off relays L^6 , L^7 , of Fig. 3, 10 I am able to dispense with choke coils $x-x'$ and connect the battery or charging generator of any type as shown in Fig. 3.

Fig. 9 shows a modified circuit in which the telephone switchboard and radio switch- 15 board are provided with multiple line connections as before, the radio switchboard having connections to the radio broadcasting transmitter T and the radio operator having a full equipment of cords and plugs of 20 known types symbolized at P^* . The sub- station is provided with a radio detector set and receiver 36, normally connected to the radio detector set through back contacts of 25 the relay L^5 , which when energized by means of the operator's key k^* at the radio board, will disconnect the receiver 36 and connect the radio detector set on its audio side directly to wires 52-53 and so through the 30 contacts of cut off relay L^4 to the line wires 16-17. As there is no battery shown for the detector set (which is typical only), the radio central battery feed is omitted in this 35 figure, which represents a very simple stand- ardized system in which however the radio operator still has perfect control for all pur- 40 poses of the substation broadcast receiver. It should be noted that the continued energi- 45 zation of relay L^5 disables the radio set, and by winding this relay so as to consume little current, this affords means to disconnect 50 the subscriber's circuit until an inspector can make his rounds and the instrument can be removed.

If it be desired to have no grounds on the 55 radio battery busses at substations, such as that on the A battery at station A' in Fig. 3, the ground wires may be carried through contacts on switch hook H' , opened when the 60 hooks are up. Many other details of operation may be introduced and changes made, without departing from the scope of my 65 invention.

Referring to the modification in which the 70 broadcast is distributed over the wires, indicated in the diagram of Fig. 10, it will be noted that the only portion of the system changed is the radio portion, that is the radio operator's circuits and the circuits of the subscriber's broadcast receiving station. 75 As the utilization of this wired radio broad- 80 casting system requires no change in the circuits of the land telephone exchange system as previously described and shown in Figs. 2 and 3, it is only necessary to substi- 85

tute Fig. 10 for Fig. 3 in disclosing this 90 modification. The conductors 16^a, 17^b, 17^a, 19^a, etc. of Fig. 10 tie on to the conductors similarly designated in Fig. 2. The circuit arrangement of Fig. 10 is substantially the same as Fig. 3 except that instead of the output of the radio transmitter T being connected to the antenna, it is connected to a wire bus 60 multiplied on to the subscriber's lines through multiplied pairs 61-64, 62-65, through suitable switch contacts 63; while 95 at the subscriber's end of the system, the primary side of the coupler circuit 29 is connected directly across the line instead of with a receiving antenna. The ordinary tuning condenser is in series in this connection with the line and prevents by-passing of the ordinary telephone currents through the said circuits. To prevent metallic multiple connection between the subscriber's lines at the central radio station the line 100 multiples are connected to the radio bus 60 through suitable blocking condensers. At the radio central station are also provided jack connections to the radio bus 60 as represented by the jack J^{10} through which the 105 radio relay unit of Fig. 11 may be connected on to the bus.

The operation of this wired radio system is similar in all respects to that of the system previously described and illustrated in 110 the circuit combinations of Figs. 2 and 3 except that carrier current broadcast is guided over the subscriber's lines from radio transmitter T, and is received at the subscriber's broadcast receiver from the line wires 19^c, 115 18^c, by way of the bridged circuit 66 connecting with the primary side of the coupler circuit 29. From the coupler connection 29 the detection, amplification, and reception of 120 the signals at the loud speaker 36 are identically the same as that described in connection with Fig. 3. The supply circuit for 125 storing the subscriber's filament battery A', the radio operator's distant control of the 130 subscriber's relay L^5 , the radio operator's testing and supervisory circuits, and circuit connections of the radio operator's multiple jacks J^2 , J^3 , J^4 for broadcasting intercommunications between the subscribers, are all 135 identically the same as that described in connection with Fig. 3. In Fig. 10, the telephone transmitter circuit at the subscriber's radio substation is the same except that it 140 has been further elaborated over that of Fig. 3, in that all the necessary contacts to 145 the subscriber's talking circuit key h' are shown with their actual connections, to enable the circuits to be readily traced. Fig. 150 10 also shows a pair of guarding contacts BK-BK' which may be opened during 155 broadcasting by the subscriber, from his broadcast transmitter T', to give the party 160 at the transmitter T' exclusive use of the 165

line over the land telephone substation and to relieve the line wire 19^c of its connection to ground through the battery A'.

If, while broadcasting is being sent out over the lines, the radio operator desires to listen in to the audio side of the subscriber's radio receiver to ascertain the quality of reception, assuming the subscriber's transmitter T' to be on its switch hook H', the radio operator plugs in on the multiple jack J³ with the testing plug P⁴ and depresses his key K' which connects the radio central battery B' to the tip side of the line and energizes the subscriber's cut-on relay L⁵. This puts the subscriber's broadcast receiver into operation, connects the telephone circuit T—H' for receiving the audio signals from the loud speaker 36 and connects the circuit from the transmitter t' on to the line and therefore over to the radio operator's circuit, all in a manner as previously described in connection with Fig. 3. For the purpose of preventing operation of the cut-off relay L⁷, at the radio central station, during the maintenance of the circuit connections just described, the radio operator's test circuit is provided with means for opening the test circuit through which relay L⁷ would ordinarily be energized. This means consists of a key k² having its contact connected in series in the test circuit and bridged by a condenser c⁵ to permit passage of the tone test current when the key contacts are opened. Thus, with the contacts of key k² open, the relay L⁷ remains deenergized preserving the connection of the central station battery with the subscriber's broadcast receiver station battery A', while subscriber's relay L⁵ is held energized over the distant control circuit which is the same as that described in connection with Fig. 3, and which may be traced from radio central battery B', through operator's listening key k' tip contacts of plug P⁴ and jack J³, line multiple 18^a, line wire 18 to subscriber's substation A', then by way of branch wire 18^c, contact of relay L⁴, conductor 26, through winding of relay L⁵ and ground back to the central station radio battery B'. Thus over the line wires there is maintained a path for the operator's distant control of the subscriber's cut-on relay, a path for power or battery supply from the central station, a path for the super audio broadcasting, and a path for audio currents from the substation to the central station for supervision of reception at the substation. The circuit connections which obtain for this condition of service are shown in the simplified or schematic diagram Fig. 12. From inspection of this diagram it will be seen that battery is supplied from the central station battery B' to the subscriber's battery A' by way of conductors 19^a, 19, contact 27^a to subscriber's battery A' and back to central station by line wires 18—19, radio operator's cord cir-

way of ground. The relay L⁵ is controlled from the radio central station by the connection from battery B' through operator's listening key k', line wire 18, relay L⁵ back to central station battery by way of ground. Connection for radio transmission from the transmitter T to subscriber's broadcast receiver is maintained by way of the radio bus 60, line multiples 62, line wires 18—19 to the primary side of the subscriber's coupler circuit 29. Connection for transmission of audio signals from the telephone transmitting circuit at the subscriber's radio receiver is maintained by way of contacts of relay L⁵, branch wires 26—67, line wires 18—19, line multiple 18^a—19^a, and contacts of listening key k' to the operator's listening set L¹⁰.

When it is desired to have the subscriber A' broadcast from the telephone transmitter T' at his radio receiving station, the radio operator plugs in on the jack J³ with his answering plug P² and plugs in on the transmitter input jack J⁴ with his calling plug P³, while the subscriber at substation A' actuates the key k' which closes the battery supply circuit of his transmitter T' and connects the secondary circuit I² to his line. The subscriber's transmitter or primary circuit may be traced from his local battery A' by way of conductor 25, conductor 42, contact of key k' transmitter T', induction coil primary winding I¹, and by way of ground back to the local battery A'. The circuit of the secondary winding I² of the induction coil may be traced across the line wires 18—19, from wire 18, over branch wire 18^c, contact of relay L⁴, wire 26, contact of relay L⁵, wire 39, secondary winding I², conductor 40, contact 27^a, conductor 67, contact of relay L⁴, through branch conductor 19^c to line conductor 19. The subscriber's talking circuit being thus connected in bridge of the line is connected on through to the input side of the central office broadcast transmitter by way of the line 18—19 multiples 18^a—19^a, jack and plug connection J³—P², through the cord circuit and plug and jack connection P³—J⁴, and through amplifier t² to the input side of the transmitter T. The transmitter T, having its output operatively connected with the line wires 18—19, as well as other lines of the exchange, the broadcasting subscriber at station A' will receive his own broadcast through his broadcast receiving apparatus.

The circuit connections existing during this condition of service are indicated in simplified form in the schematic circuit diagram of Fig. 13. From inspection of Fig. 13, it will be seen that audio currents originating at I² will be transmitted over the line to the central station by way of conductors 39—40, contacts 27^a—27^c, conductors 26—67, line wires 18—19, radio operator's cord cir-

cuit and plug connection JP, amplifier t^2 to transmitter T. The output side of the transmitter T is connected to the line wires 18-19 through line multiples 62, while the 5 input side or coupler 29 of the subscriber's broadcast receiver is connected across the line 18-19 through the pair of conductors 66. The broadcast transmitter T is, of course, multiplied to other lines not shown. Thus 10 with the circuit arrangement of Fig. 13, the subscriber may transmit broadcast matter at audio frequency over the line to the central station and receive at super audio frequency over the same line.

15 Should it be desired to have a subscriber broadcast from his ordinary land phone substation, the radio operator connects the subscriber's line with the input side of the broadcast transmitter T through jack J^3 , plug P^2 , P^2 , J^4 , input amplifier t^2 to radio transmitter T. The subscriber is now supplied with telephone transmitter current and has telephonic connections over the line as in the usual land phone system except that 20 his battery supply line supervision and other connections are maintained through the radio operator's cord circuit instead of through the telephone exchange switch boards. The output side of the transmitter 25 T is connected to the various line wires as before described so that intelligence sent out by this subscriber's station is sent back over his own lines and other lines in the form of wire guided radio, which may be picked up 30 by the different subscribers' broadcast receivers through their coupler connections 29 and multiple pairs 66 tapped to their respective line wires.

35 The connections maintained during this 40 condition of service are shown in the simplified or schematic diagram of Fig. 14, where it will be seen that the broadcasting subscriber at station A' is supplied with transmitter current from the central office battery B' over the line wires 18-19, and that the receiver or outgoing telephone circuit is connected across the line, all in the usual and well known manner of land phone practice. The exception is that the subscriber's line 45 18-19 is connected through the radio operator's plug and jack connection PJ, and the input amplifier t^2 to the input side of the radio or broadcast transmitter which has its output end connected to the lines for wire 50 guided broadcasting. This broadcast may be taken off the line wires 18-19 at the broadcast receiver station of the broadcasting subscriber, as well as the broadcast receiving station of other subscribers, through the coupler connection 29 and multiple pair 66 connected across the line wires. It will be 55 noted that during this connection the subscriber's broadcast cut-off relay L^4 is energized, maintaining its contacts open and thereby relieving the line of all straight 60

65 metallic connections with the broadcast receiver circuit. It will further be noted, that in this arrangement of the circuits the line conductors serve simultaneously to transmit power or transmitter current supply from 70 the central station to the substation, audio currents from the substation to the central station and guided high frequency currents from the central station to the substation.

75 In the simplified diagram, Fig. 15, I have shown a form of the invention in which the means for enabling the radio operator to listen in on the audio reception at the subscriber's broadcast station, is simplified. This consists in providing means for electrically connecting the audio output circuit of the subscriber's broadcast receiver across the line wires 18-19, through suitable switching and coupling means. This connection is established by closure of the 80 switch contacts 73, and 70 which connects the audio circuit of the broadcast receiver across the line wires by way of primary winding 69 of the repeat coil RC, secondary winding 68, contacts 70, branch wire pair 71 85 to line wires 18-19.

90 In the operation of this circuit arrangement the radio operator communicates with the subscriber either over the land phone or by way of the broadcast system and instructs him to establish the test circuit connections by closing the contacts 73 and 70, whereby the radio broadcasting sent out from transmitter T over the multiple conductor 65 and line 18-19, is received at the 95 subscriber's broadcast receiver through the coupler connection 29, transformed into currents of audio frequency and sent back by way of contacts 73, repeat coil RC, branch wires 71, line 18-19, to the radio central station and thence through contacts of the radio operator's listening key L^1 to the listening set L^1 . At the same time, battery charging current is transmitted from the central office battery B over line wire 19 and contacts 74 to the subscriber's filament battery A'. It will be seen that with this arrangement of circuit connections the line wires 18-19, as in the arrangement of Fig. 14, 100 serve to simultaneously transmit power or 105 battery supply from the central station to the substation, to transmit radio frequency currents from the central station to the substation and to transmit audio frequency currents from the substation to the radio 110 station.

115 I claim:

120 1. The combination of a plurality of telephone substations, a central station, a line 125 radio broadcasting transmitter at said central station, a receiver therefor at each substation, a wire line connecting each substation with the central station and a telephone on each line at each substation, with means 130 at the central station to direct modulated

waves from said broadcasting transmitter over said wire lines to said receivers, other means to interconnect the substations for conversation through said wire lines, and

means also at said central station supplying operating energy to the receivers at the substations each over its individual wire line.

2. A combined telephone and line radio broadcasting system, comprising a plurality of telephone substations, a telephone and a high frequency receiver at each substation, a central station common to said substations, individual line wires interconnecting the central station and the substations, means to direct high frequency modulated waves over said line wires to the substation high frequency receivers, and common means at the central station supplying operating current to both telephones and high frequency receivers over their respective individual line wires, with means at each substation to differentiate between the high frequency waves, operating current and the telephone currents, and to prevent interference.

3. In a broadcasting system, a main station, a plurality of substations, and individual wire circuits from the main station to the substations, means at said main station for generating and transmitting over said wire circuits to the substations high frequency modulated waves, means at the substations for receiving said waves, with means at the main station controlling the wave receiving means at the substations over said wire circuits.

4. In a broadcasting system, a main station, a plurality of substations, and individual wire circuits from the main station to the substations, means at said main station for generating and transmitting over said wire circuits to the substations high frequency modulated waves, means at the substations for receiving said waves, with a centralized source of current supply for the substation receiving means, connected to said wire circuits and distributed thereby individually and directly to the several substations.

5. A broadcasting system comprising a primary station, a secondary distributing station, and a plurality of local receiving stations connected through wire lines to the secondary station and all in permanent tune therewith, means at said secondary station to receive broadcast waves from the primary station at its wave length, and to relay and redistribute the same over said wire lines in its own area at the standard wave length to which its receiving stations are tuned, and means also at said secondary station to determine over said wire lines when its transmitter is actually tuned to the fixed wave length of its receiving stations.

6. In a radio-telephone system, a transmitting station, a receiving station, a line radio

transmitter at the transmitting station for transmitting high frequency modulated waves, a receiving set at the receiving station tuned to receive said waves, and a wire circuit connecting the two stations with means to connect it from said line radio transmitter through local wave receiving connections to the receiving set at the receiving station, and means at the transmitting station to control said connecting means, over the same wire circuit.

7. A broadcasting system comprising one or more primary transmitting stations operating at variable wave lengths, a localized secondary station having receiving means capable of variable tuning to receive said variable broadcast waves, and transmitting means connected therewith for relay modulation, but tuned for a fixed wave length, and a plurality of receiving stations connected to the transmitting means at said secondary station by wire circuits, and having receiving sets tuned to the fixed wave length of said station, with means controlled by an operator at said secondary station and operable through said wire circuit to maintain said secondary station transmitting means in constant tune with said local station receiving sets.

8. The combination of a plurality of substations, a central station, a line radio broadcasting transmitter at said central station; a high frequency receiver at each substation, a wire line connecting each substation with the central station and a telephone on each line at each substation, with means at the central station to interconnect the substations for conversation through said wire lines, means also at said central station controlling the operation of the high frequency receivers at said substations over said wire lines, and other means to connect said line wires individually to said line radio broadcasting transmitter, so as to transmit high frequency modulated waves thereover to the subscriber's receiver.

9. The combination of a plurality of stations, a central station, a line radio broadcasting transmitter at said central station, a high frequency receiver at each substation, a wire line connecting each substation with the central station and a telephone on each line at each substation, with means at the central station to interconnect the substations for conversation through said wire lines, means at said central station to connect said line radio broadcasting transmitter with said wire lines, and means also at said central station for connecting and disconnecting the high frequency receiving apparatus at said substations from said wire lines.

10. A line radio system of intercommunication comprising a central station, a plurality of substations related thereto, and in-

- dividual circuits interconnecting the same, each circuit composed of a high frequency link and a low frequency return, both related to and guided over the same wire line, 5 and transmitting and receiving means located at the central station and at the substations, adapted to interrelate the high frequency waves and the wire currents on said wire line so that modulated high frequency 10 waves may be transmitted in one direction, and corresponding demodulated waves may be returned over the wire circuit in the other direction, with means at the central station to control the transmitting means at each 15 substation over the same wire line.
11. A line radio system of intercommunication comprising a central station, a plurality of substations related thereto, and individual circuits interconnecting the same, 20 each circuit composed of a high frequency link and a low frequency return, both related to and guided over the same wire line, and transmitting and receiving means located at the central station and at the substations, adapted to inter-relate the high frequency waves and the wire currents on said wire line so that modulated high frequency 25 waves may be transmitted in one direction, and corresponding demodulated low frequency waves may be returned over the wire circuit in the other direction, with switches 30 at the substations controlling the relation of received and transmitted waves, and means at the central station for controlling said switches over the same wire line.
12. A line radio system of intercommunication comprising a central station, a plurality of substations related thereto, and individual circuits interconnecting the same, each circuit composed of a high frequency 35 link and a low frequency return, both related to and guided over the same wire line, and transmitting and receiving means located at the central station and at the substations, adapted to inter-relate the high frequency 40 waves and the wire currents on said wire line so that modulated high frequency waves may be transmitted in one direction, and corresponding demodulated low frequency 45 waves may be returned over the wire circuit in the other direction, with means at the central station to control the receiving means at each substation over the same wire line.
13. A line radio system of intercommunication comprising a central station, a plurality of substations related thereto, and individual circuits interconnecting the same, each circuit composed of a high frequency link and a low frequency return, both related to and guided over the same wire line, 55 and transmitting and receiving means located at the central station and at the substations, adapted to inter-relate the high frequency and the wire currents on said wire line so that modulated high frequency waves 60

may be transmitted in one direction, and corresponding demodulated low frequency waves may be returned over the wire circuit in the other direction, with means at the central station to control the substation operation over the same wire line. 70

14. A line radio system of intercommunication comprising a central station, a plurality of substations related thereto, and individual circuits interconnecting the same, 75 each circuit composed of a high frequency link and a low frequency return, both related to and guided over the same wire line, and transmitting and receiving means located at the central station and at the substations, adapted to interrelate the high frequency waves and the wire currents on said wire line so that modulated high frequency waves may be transmitted in one direction, and corresponding demodulated low frequency waves may be returned over the wire circuit in the other direction, with switches 80 at the substations controlling the relation of received and transmitted waves, and means at the central station for controlling said switches over the same wire line. 85

15. A combined telephone and line radio broadcasting system comprising a plurality of telephone substations, a telephone central station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station. 90

16. A combined telephone and line radio broadcasting system comprising a plurality of telephone substations, a telephone central station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station, together with means controlled by a telephone subscriber in calling to disconnect the wire connections between his telephone and the corresponding line radio receiver. 105

17. A combined telephone and line radio broadcasting system comprising a plurality 110

of telephone substations, a telephone central station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station, together with means at each line radio substation to control the actuating circuits of the line radio and means also at said line radio substations for effecting telephone connection with the corresponding line circuit.

18. A combined telephone and line radio broadcasting system comprising a plurality of telephone substations, a telephone central station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station, and means controlled by an operator at the line radio central station to connect and disconnect the wire circuits for telephonic communication between each line radio substation and the corresponding telephone substation.

19. A combined telephone and line radio broadcasting system comprising a plurality of telephone substations, a telephone central station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station, together with a centralized source of current supply at each of the central stations, both said sources feeding independently through the line wires to the telephone substations and to the line radio substations respectively.

20. A combined telephone and line radio broadcasting system comprising a plurality of telephone substations, a telephone cen-

tral station, line wires interconnecting them, a plurality of line radio substations, a line radio central station, means to transmit messages from said line radio central station over said line wires to its substations by modulated high frequency waves, means at the line radio substations to transmit messages over same line wires telephonically, wire connections between the line radio substations and the telephone substations, and wire connections between the line radio central station and the telephone central station, together with a centralized source of current supply at each of the central stations, both said sources feeding independently through the line wires to the telephone substations and to the line radio substations respectively, and means controlled by an operator at the telephone central station to disconnect the line radio central battery from a line when in use for telephonic conversation.

21. A combined telephone and line radio system of intercommunication comprising a central station, subscribers' substations, means for interconnecting said subscribers' substations through the central station for conversation, line radio means for broadcasting said intercommunicating conversation, line radio receiving means at the substations, and means at the central office for supervising the reception at said substations.

22. In a broadcasting system, a central station, a plurality of substations, means at said central station for generating and transmitting to the substation modulated high frequency waves, means at the substations for receiving said waves, individual wire circuits from the main station to the substations, with means at the main station controlling the wave receiving means at the substations over said wire circuits, and means for putting a characteristic busy test signal on an individual wire circuit during the control of the wave receiving means associated with the said individual wire circuit.

23. A combination telephone and line radio broadcasting system comprising a plurality of telephone substations, a telephone central station, line wires interconnecting them, a plurality of line radio substations, a line radio central station, means to transmit messages from said line radio central station to its substations by modulated high frequency waves, means at the line radio substations to transmit messages telephonically, wire connections between the line radio substations and the telephone substations, wire connections between the line radio central station and the telephone central station, a source of direct current supply at the telephone central station feeding through the line wires to the respective telephone substations, storage batteries at the line radio substations.

and means at the central station for charging said storage batteries over the line circuits.

24. In a radio telephone system, a central station, a subscriber's substation, a wire circuit connecting the substation with the central station and provided at the central station with a line cut-off relay, a high frequency receiver at said substation, means for supplying said receiver with current from the central station over the line circuit, a cut-off relay for controlling the connection of said supply means to the line circuit energized upon energization of said line cut-off relay.

25. In a radio telephone system, a central station, a subscriber's substation, a wire circuit connecting the central station with the substation, and means for simultaneously transmitting over said wire circuit, high frequency signalling current from said central station to said subscriber's station, audio frequency signalling current from the subscriber's station to the central station and controlling current for distant control of the circuits at the subscriber's station from the central station.

26. In a line radio telephone system, a central station, subscribers' substations and transmitters therefor, wire circuits connecting the central station with the substations, and means for simultaneously transmitting over said wire circuit, current supply from the central station for the subscriber's telephone transmitter, audio frequency currents from a subscriber's station to the central station, and super audio frequency currents from the central station to the same and

other subscribers' stations modulated by said audio frequency currents, whereby a subscriber broadcasting to other subscribers is afforded means for simultaneously comparing the matter as received with the original production.

27. In a line radio telephone system, a central station, a plurality of subscribers' stations, a wire circuit individually connecting the central station with each substation, a high frequency receiver at each said substation, a thermionic tube therefor, common means for supplying modulated high frequency currents to all said tubes over said wire circuits, and common means for supplying filament current for all said tubes from the central station each over its individual wire circuit.

28. In a line radio telephone system, a central station, a subscriber's substation, a wire circuit connecting the central station with the substation, a wave transmitter arranged to transmit audio modulated high frequency waves over the wire circuit, a receiving set at the substation tuned to receive said waves and operatively connected to the said wire circuit, and means for feeding electrical power from the central station over the wire circuit to the substation high frequency receiver set, together with means for transmitting audio frequency output currents from the high frequency receiving station back to the central station over the wire circuit.

In testimony whereof I hereunto affix my signature.

EDWARD E. CLEMENT.
